UNITED STATES PATENT OFFICE.

CHARLES D. ARMSTRONG, OF PITTSBURGH, PENNSYLVANIA, ASSIGNOR TO ARMSTRONG CORK COMPANY, OF PITTSBURGH, PENNSYLVANIA, A CORPORATION OF PENNSYLVANIA.

FLOOR-COVERING.

1,134,578.

Specification of Letters Patent.

Patented Apr. 6, 1915.

Application filed June 24, 1913. Serial No. 775,518.

To all whom it may concern:

Be it known that I, CHARLES D. ARMSTRONG, a citizen of the United States, residing at Pittsburgh, in the county of Allegheny and State of Pennsylvania, have invented a new and useful Improvement in Floor-Covering, of which the following is a full, clear, and exact description, reference being had to the accompanying drawings, forming part of this specification, in which—

Figure 1 is a plan view partially broken away showing a portion of my improved floor covering; and Fig. 2 is a vertical cross-section of the same in place.

In the applying of linoleum tile upon a rigid base such as concrete, it has been found that there is not sufficient resilience to form a proper surface for walking, the linoleum tiles not giving a sufficient yielding quality. These tiles if made soft will become injured or destroyed within a short time, and if made harder they do not sufficiently relieve the rigidity of the cement or other rigid flooring. I have overcome this objection by interposing between the linoleum tiles and the rigid base such as concrete, a cushioning layer, which is preferably formed of some cork material such as cork carpet or baked sheet cork. These tiles are usually cut from linoleum sheets and laid in place on the cement foundation to form the desired pattern, being secured by glue or cement.

In carrying out my invention, I first secure to the surface of the concrete or other rigid foundation or base a cushioning layer, preferably about three-eighths of an inch thick, and which is preferably formed of cork carpet, which is softer than linoleum, or of baked sheet cork. This cushion layer is secured to the cement or other rigid foundation by a cement, either waterproof or non-waterproof, as desired. The linoleum tiles are then laid in the proper order and shape on the cushioning layer, and are secured thereto by any desirable cement whether waterproof or not.

In the drawings, 2 represents the foundation or flooring of rigid material such as cement; 3 the intermediate cushioning layer; and 4 the linoleum tiles. The linoleum tiles are relatively hard compared to the cushioning layer, although the cushion-

ing layer preferably contains or is formed of cork, though it may be of felt or other cushioning material. The total thickness of the two coverings over the cement is preferably from one-half to three-fourths of an inch.

I do not wish to confine myself to the method of formation of the covering herein described, as it is obvious that instead of securing the cushioning or backing member on the floor before laying the tile, such member may be applied in other ways, as securing it to the tiles before laying them.

The advantages of my invention result from the use of the cushioning layer between the rigid base or floor and the tiles which are secured in place in the desired pattern. I am thus enabled to use linoleum tiles of a hard nature which will stand hard usage while obtaining the cushioning action and resilience which the tiles would not give.

I claim:—

1. The combination with a rigid floor or base, of a yielding elastic floor covering, comprising a plurality of pieces or blocks of cork composition secured to the rigid floor, and linoleum tiles secured to and covering the upper faces of the composition blocks, said tiles and cushioning blocks being arranged to yield when pressure is exerted on the linoleum tiles, substantially as described.

2. The combination with a rigid floor or base, of a yielding elastic floor covering, comprising resilient linoleum tiles laid edge to edge and a cushioning layer of cork material secured to the floor and the lower faces of the linoleum tiles, said linoleum tiles being harder than the cushioning layer but adapted to yield under pressure, substantially as described.

3. As a new article of manufacture, a composite block for floor covering, comprising a block linoleum wearing portion and a resilient cork composition backing member secured thereto, substantially as described.

In testimony whereof, I have hereunto set my hand.

CHARLES D. ARMSTRONG.
